CLAIM

The ornamental design for a combined pressure reducer and fertilizer dispenser, as shown or described.

DESCRIPTION

FIG. 1 is a perspective view taken from the top, front and right side of a combined pressure reducer and fertilizer dispenser showing our new design;

FIG. 2 is a top plan view thereof;

FIG. 3 is a left side elevational view thereof;

FIG. 4 is a bottom plan view thereof;

FIG. 5 is a rear elevational view thereof; and

FIG. 6 is a front elevational view thereof.

FIG. 1

FIG. 2

FIG. 3

FIG. 4

FIG. 5

FIG. 6
